COIN BANK

David H. Zell, Brooklyn, N. Y.

Application June 1, 1935, Serial No. 24,491

5 Claims. (Cl. 194—74)

This invention relates to coin banks and has for its primary object to provide a bank having a self-contained calendar, actuated upon the daily deposit of a coin, as an aid in the methodical accumulation of savings, for the payment of insurance premiums and for other purposes.

Another object of the invention is to provide a very simple construction and arrangement of the calendar mechanism and its actuating means upon a separate supporting plate, mounted within the bank body to occupy a minimum of space therein.

A further object is to provide actuating means for the calendar mechanism which eliminates the use of gears, ratchets or the like, while obtaining an accurately controlled movement of the day and month indicating disks.

It is also an important object of the invention to provide a coin operated actuating member for the day indicating disk, means beneath the coin receiving slot of the bank for supporting and positioning the deposited coin relative to said member, and a manually operable member mounted on said coin supporting means, having a part projecting outwardly through said slot and operable to engage the coin with said actuating member.

With the above and other objects in view the invention consists in the improved coin bank and in the form, construction and relative arrangement of its several parts, as will hereinafter be more fully described, illustrated in the accompanying drawing and subsequently incorporated in the subjoined claims.

In the drawing, wherein I have illustrated one simple and practical embodiment of my invention and in which similar reference characters designate corresponding parts throughout the several views:

Figure 1 is a front elevation, showing one form of coin bank provided with my present invention.

Fig. 2 is a vertical sectional view, taken substantially on the line 2—2 of Fig. 4.

Fig. 3 is a fragmentary section, similar to Fig. 1, showing the coin in operative engagement with the calendar disk actuating member.

Fig. 4 is a transverse vertical section, on an enlarged scale, taken substantially on the line 4—4 of Fig. 2.

Fig. 5 is a horizontal sectional view, taken substantially on the line 5—5 of Fig. 2, the body of the bank being omitted.

Referring in detail to the drawing, the body of the bank may be of any desired ornamental shape or form. As herein shown, the front and

back walls 5 and 6 respectively have their outer surfaces covered by a flexible sheet material 7, such as leather, celluloid or the like, which may be embossed or otherwise suitably ornamented. The opposite edge walls 8 and top wall 9 of the bank are formed from a continuous sheet metal strip, suitably secured at its edges to the front and rear walls 5 and 6. The bottom of the bank is closed by a door 10, pivotally mounted at one of its ends upon the bank walls, as at 11. This door carries suitable key actuated locking mechanism, generally indicated at 12, to coact with the keeper means 13 and lock the door in closed position, with the outer face thereof substantially flush with the lower edges of the walls 5, 6 and 8 15 of the bank body.

The top wall 9 of the bank, adjacent to one side edge thereof, is provided with a longitudinally extending, depressed portion 14, having a coin receiving slot 15.

Upon a separate supporting plate 16 the calendar mechanism and its actuating means are mounted. The outline form of this plate conforms to the walls 5 and 6 of the bank and at its lower end is formed with an angularly offset depending flange 17 having spaced slots to receive bendable tongues 18, struck from the wall 5 and clinched upon said flange. At its upper end the plate 16 is provided with a horizontal flange 19 abutting at its free edge against the rear longitudinal edge of the top wall 9 of the bank. This flange has a slot 20 therein to register with the coin receiving slot 15.

The plate 16, above its center, is provided with a circular offset portion 21, having a concentric opening 22 to receive the rearwardly offset portion 24 of the day indicating disk 23 of the calendar. The disk is retained in rotatable connection with the supporting plate by means of the metal cap 25, secured to the rear face of the part 24 by the tongues 26, struck from said cap plate and extending through apertures in the part 24 and clinched thereon. The outer edge portion of the cap 25 projects beyond the opening 22 and upon the rear face of the plate 16. The disk 23 and plate 25 are centrally provided with suitable registering openings 27 and 28 respectively, to receive the end of a resetting key inserted through a grommet 29 fixed in the rear wall of the bank.

The front surface of the disk 23 at its margin is marked with the numerals 1 to 30, and between the numerals 1 and 30 a single tooth 30 projects slightly from the periphery of the disk. In 55

radial alignment with each of said numerals the disk is provided with an opening 31.

The month indicating disk 32 is rotatably mounted below the disk 23, upon a second forwardly offset circular portion 33 of the plate 16, by means of a tubular rivet or grommet 34. Between adjacent month designations on the front face of this disk the edge thereof is provided with the notches or recesses 35. The edge faces 10 of the disk between these notches are curved on concave arcs, as at 36, so that they will closely fit against the convex periphery of the disk 23.

At the rear side of the plate 16, immediately beneath the flange 19, a guide plate 37 is arranged in parallel relation therewith, and attached thereto in any preferred manner. One end of this guide plate is relatively narrow, as shown at 38. The wider portion of said plate has a flange 39 at its lower edge, which abuts 20 the rear face of the plate 16 and forms a stop and support for the coin inserted through the slot 15. This flange also supports the manually operable slide 40, having the finger piece 41 projecting upwardly through the coin slot 15. A 25 spring 42 normally holds the slide in a retracted position with the finger piece in one end of said slot.

Upon the front side of the plate 16 the actuating member 43, of resilient sheet metal, is pivoted at 44. This member has an arm 45 terminating in a lug 46, projecting rearwardly through an opening 46' in the plate 16 and beneath the free lower edge of the part 38 of the guide plate 37. Adjacent to the arm 45 a second arm 47 35 on said member has a forwardly projecting terminal lug 48 bearing against the rear face of the disk 23. A third arm 49 on said member extends downwardly from the arm 47 and at its free end has a forwardly projecting lug 50, also bearing 40 against the rear face of the disk 23.

A spring 51 yieldingly holds the member 43 in a normal position, with the lug 46 bearing against the upper edge of the opening 46'.

Below the arm 49 of the actuating member 43 45 a light leaf spring 52 is secured to the plate 16 and at its free end bears against the rear face of the disk 23 in line with the circular row of openings 31 therein.

The part 38 of the guide plate 37 is provided, 50 adjacent to its lower edge, with a forwardly punched part or protuberance 53. The distance between this protuberance and the adjacent end of the supporting flange 39 of the guide 37 is somewhat less than the diameter of the coin, and 55 in the normal position of the member 43 of the lug 46 is disposed between said protuberance and the end of the coin supporting flange.

From reference to Fig. 4 of the drawing it will 60 be seen that when the supporting plate 16, with the mechanism above described, is mounted within the bank body, the day and month indicating disks 23 and 32 are positioned adjacent the front wall 5, in parallel relation therewith. Flanges 16' extend along opposite side edges of said supporting plate and contact closely with the edge walls 8 of the bank body, and in conjunction with the tongues 18 and the flange 19, serve to very rigidly fix said plate in position with respect to the bank body.

70 An ornamental escutcheon 54 is secured to the front wall 5 of the bank and has vertically spaced sight openings through which the day and month designations on the disks 23 and 32 respectively may be read.

75 The operation of my invention may be read-

ily understood from the above description. Upon the insertion of the coin through slot 15 it is supported in a vertical position upon the flange 39 of the guide plate 37, at one side of the slide member 40. The projection 41 is now engaged by the finger and the slide 40 shifted to the left from the position shown in Fig. 2. The coin, indicated at C, is thus also moved between plate 16 and guide 37 so that the edge of the coin bears upon the lug 46 of the actuating member 43. 10 As the movement of the coin continues one side thereof contacts with and rides over the protuberance 53, against the yieldable resistance of the end portion 38 of the guide plate 37, which insures continuous bearing contact of the coin 15 on lug 46. Member 43 is thus pivotally moved toward the outer edge of the calendar disk 23 until the lug 48 on arm 47 engages in one of the openings 31 in said disk, the disk being held against anti-clockwise rotation by the spring 52. 20 At this time the coin passes beyond the lug 46 and falls into the bank.

From reference to Fig. 2 of the drawing it will be noted that there is clearance between the periphery of the coin and the top wall of the 25 bank case. Therefore if the coin had unrestricted rolling movement and the member 41 were quickly actuated, initially the coin would roll over the lug 46 without depressing the same until the coin at its upper edge contacts with 30 the top wall of the case. On the other hand, if the member 41 was slowly actuated, due to the angle of pressure transmitted through the coin to the lug 41 there would be an immediate depression of the lug upon initial contact of the 35 coin therewith. The provision of the parts 38 and 53 insures the latter actuation of the member 43 under all operating conditions, as sufficient resistance is thereby provided to prevent the free rolling movement of the coin over the 40 lug 46 in its initial engagement therewith. This frictional resistance to the rolling movement of the coin is sufficient to counteract the tendency of spring 51 to force the coin upwardly by contact of lug 46 therewith and into engagement 45 with the top wall of the bank. In other words the provision of the parts 53 and 38 assures a horizontal straight line movement of the coin. Accordingly the same extent of downward movement of lug 46, and of rotative movement of disk 50 23 is assured in every operation.

When pressure on the lug 46 is thus released spring 51 contracts and reverses the pivotal movement of the actuating member 43, so that the lug 48 on the arm 47 coacts with the disk 23 to rotate the latter one step, and expose the day numeral corresponding to the day of the month when the deposit is made, through the upper opening 55 in the escutcheon 54. The arm 49 acts as a brake against the rear face of the 60 disk 23 and the lug 50 on said arm engages in one of the openings 31 in said disk to positively check and limit the movements of the disk, so that the day indicating numerals thereon will accurately register with the sight opening. The 65 end of the leaf spring 52, engaging in another of the openings 31, prevents retrograde rotary movement of the disk 23.

When the disk 23 has been operated in this manner until the numeral 30 is exposed, upon 70 the next operation thereof, the tooth 30 of said disk engages in one of the notches 35 of the disk 32 and moves the latter one step to expose the proper month designation thereon through the lower sight opening 55. 75

From the above description it will be seen that the invention provides a very simple and compact construction and arrangement of the several parts, dispensing with the use of gears, ratchets and similar elements, while insuring positive and accurate operation of the mechanism. Direct co-action of the periphery of the disk 23 with the arcuate surfaces of the disk 32 effectually prevents rotation of the latter disk from its set position. The supporting plate 16 upon which the calendar mechanism is carried enables said mechanism to be properly positioned within the bank body with a minimum expenditure of time and labor.

I have herein shown a very desirable and practical embodiment of my invention, which has been found entirely satisfactory in practical use. It will, however, be understood that the essential features thereof may also be exemplified in numerous other alternative structural forms. Accordingly, I reserve the privilege of resorting to all such legitimate changes in the form, construction and relative arrangement of the several elements as may be fairly considered within the spirit and scope of the appended claims.

I claim:

1. A coin bank having a slot in one marginal wall thereof for the insertion of coins, mechanism for registering the insertion of a coin, housed within the bank and having a coin operated actuating member, a manually operable element, and a common guideway for said element and the coin supporting the latter in a vertical position for rolling movement, said actuating member having an angularly disposed lug at one end of the guideway, said element being operable to engage and project the coin through the guideway into engagement with said lug, and one wall of the guideway having means yieldably coacting with the coin to hold the same in moving contact with said lug.

2. A coin bank having a slot in one marginal wall thereof for the insertion of coins, registering mechanism housed within the bank adjacent to one of its side walls, said mechanism including a registering disk, a pivoted actuating member for said disk positioned wholly at one side of a vertical plane which includes the axis of said disk, a spring holding said member in normal position relative to said disk, said member having spaced relatively fixed parts, one of said parts adapted to be engaged by a coin inserted through said slot to move said member from its normal position, the other of said parts adapted to coact with means on said disk to rotate the latter upon return movement of said member to normal position under the action of said spring, and a third part carried by said actuating member and coacting with the disk to limit such rotation of the disk in each actuation of said member.

3. A coin bank having a slot in one marginal

wall thereof for the insertion of coins, a plate fixed within the bank in spaced parallel relation to one of its side walls, a manually operable element mounted on one side of said plate and having an operating part projecting outwardly through said slot, a support on said side of the plate beneath said slot to support an inserted coin for rolling movement in position to be engaged by said manually operable element, a registering disk rotatably mounted at the opposite side of 10 said plate, and a coin operated member movably mounted on the latter side of the plate, said member having a part extending between said plate and the registering disk and coacting with means on the latter to actuate said disk when said member is engaged and actuated by a rolling coin.

4. A coin bank having a slot in one marginal wall thereof for the insertion of coins, a plate fixed within the bank in spaced relation to one of its side walls, a support on one side of said 20 plate beneath said slot to receive and support a coin in vertical position for rolling movement, a spring held manually operable element mounted on said support, a coin operated actuating member movably mounted on the opposite side of said 25 plate and having an angularly disposed lug extending through an opening in the plate; into the path of rolling movement of the coin, a registering disk rotatably mounted at the latter side of said plate, and said actuating member having 30 a resiliently yieldable part positioned between said plate and the registering disk and coacting with means on said disk to actuate the same when said element is operated to project the rolling coin beyond said support and into bearing contact with 35 the lug of said actuating member.

5. A coin bank having a slot in one marginal wall thereof for the insertion of coins, a plate fixed within the bank in spaced relation to one of its side walls, a support on one side of said 40 plate beneath said slot to receive and support a coin in vertical position for rolling movement, a spring held manually operable element mounted on said support, a coin operated actuating member movably mounted on the opposite side of said 45 plate and having an angularly disposed lug extending through an opening in the plate into the path of rolling movement of the coin, a registering disk rotatably mounted at the latter side of said plate, and said actuating member having 50 a resiliently yieldable part positioned between said plate and the registering disk and coacting with means on said disk to actuate the same when said element is operated to project the rolling coin beyond said support and into bearing contact with 55 the lug of said actuating member, and said support having a resiliently yieldable part projecting from one end thereof and positioned above said lug adapted to resiliently bear against one side of the coin to retain the latter in rolling 60 contact upon the lug.

DAVID H. ZELL.
